Fig. 3

Fig. 4

Fig. 7

FIGS. 1 and 2 are respectively front and side views of a side chair with arms embodying the design.

FIGS. 3 and 4 are respectively front and side views of a lounge chair with arms embodying the design.

FIGS. 5 and 6 are sectional views taken respectively along the sections 5 and 6 of FIG. 2.

FIG. 7 is a perspective view of a chair as shown in FIGS. 3 and 4.

The dominant feature of the design shown in the above figures is a hub structure, which is shown in the figures at the top of each of the vertical legs of the illustrated chairs incorporating such hub structure.

We claim:

The ornamental design for a chair, as shown and described.
